UNITED STATES PATENT OFFICE.

EMIL A. NELSON, OF RONVILLE, MICHIGAN.

INTERNAL-COMBUSTION ENGINE.

1,247,318.

Specification of Letters Patent. Patented Nov. 20. 1917.

Application filed December 17, 1914. Serial No. 877,656.

To all whom it may concern:

Be it known that I, EMIL A. NELSON, a citizen of the United States of America, residing at Ronville, in the county of Wayne 5 and State of Michigan, have invented certain new and useful Improvements in Internal-Combustion Engines, of which the following is a specification, reference being had therein to the accompanying drawings.

10 This invention relates particularly to a construction and arrangement of head for internal combustion engines, and its object is to provide a simple and compact arrangement of valve and valve operating 15 mechanism carried by the head; and further to provide a construction and arrangement whereby the parts are effectually lubricated and the lubricant prevented from entering the combustion chamber of the engine. It 20 is also an object of the invention to so construct the head as to provide an air passage therethrough for supplying warm air to a carburetor; and to provide certain other new and useful features in the construction 25 and arrangement of parts, all as hereinafter more fully described and pointed out in the appended claims reference being had to the accompanying drawings in which—

Figure 1 is a longitudinal vertical section through the upper portion or head of 30 an engine embodying the invention;

Fig. 2 is a transverse vertical section of the same upon the line $\alpha-\alpha$ of Fig. 1;

Fig. 3 is a similar view upon the line 35 $y-y$ of Fig. 1, and

Fig. 4 is a horizontal section upon the line $z-z$ of Fig. 3.

In the drawings, the invention is illustrated as applied to a four cylinder engine 40 but it will be understood that it may be constructed for any desired number of cylinders.

The upper ends of the several cylinders are indicated at 1 and these are faced off to 45 receive the head 2 which is bolted in place thereon in the usual manner. The head is formed to provide a continuation of each cylinder, this extension or continuation being provided to form a compression chamber 50 having seats formed around openings in its upper end wall for inlet valves 3 and exhaust valves 4.

As shown in Fig. 4 the head is formed with an inlet passage 5 having branches 6 55 each leading to a pair of inlet valves, and also with outlet passages 7 and 8 leading

from the end exhaust valves and a center passage 9 leading from the two adjacent center exhaust valves. A water space 10 surrounds all of these passages and communicates with the water jacket in the cylinders. A single exhaust pipe 11 is attached to the side of the head to receive the exhaust from the passages 7, 8 and 9 and the outlet end of any suitable form of carburetor 12 is 60 secured over the inlet passage 5 to supply combustible charges thereto. The water space is provided with suitable water connections 13 and 14.

Each valve has an integral valve stem 15 70 extending upwardly through a suitable bearing 16 and is provided with a coiled spring 17 sleeved thereon between the end of the bearing and a suitable washer 18 upon the upper end of the stem forming a seat for the 75 spring which acts to hold the valve seated.

A cap or sleeve member 19 having a closed and suitably formed upper end 20 incloses the upper end of the stem and spring with its end wall engaging the upper end of the 80 stem and its side wall fitting within a suitable guide 21 forming an integral part of the head and within which guide the cap is free to slide.

A cam shaft chamber 22 extends across 85 the several cylinders and is formed integral with the several guide portions 21 which form necks or connecting portions between the head proper and the chamber 22 into which the extreme upper ends of the several 90 valve stems project with their guide sleeves 19 inclosing said ends and contacting the several operating cams 23 on a cam shaft 24 which is mounted at one end in a suitable bearing 25 in the end of the cam shaft chamber, a like bearing (not shown) being provided for the shaft at the opposite end of the chamber. Intermediate bearing walls 26 extend across the chamber and form bearings for enlarged portions 27 of the cam 95 shaft. A cover plate 28 closes the upper end of the cam shaft chamber and is secured in place by suitable bolts 29, and a wall 30 at each end of the chamber, extends upwardly to the plane of the seat for the cap and outside of each of these walls is a space 31 in 100 communication with a passage 32 which extends downwardly at each end of the head and alongside the end cylinders to the crank case (not shown) of the engine. Oil is supplied to the cam shaft chamber through a 105 suitable connection 33 and fills this cham-

110

ber to the upper edge of the walls 30 over which it flows into the space 31 and drops down the passage 32 to the crank case of the engine. The cam shaft and its cams are 5 thus immersed in oil and the upper ends of the sleeve caps 19 which project into the cam shaft chamber are also covered by the body of oil.

To prevent the cap sleeves 19 from turning in their guides, each is provided with a slot 34 in one side to receive a pin 35 engaging a screw-threaded opening in the side of the guide portions 21, and extending across the full length of the head, at the 10 lower end of the several guides 21, is a passage 36 which opens at its ends into the passages 32 so that any oil which may work downwardly from the cam shaft chamber around the several cap sleeves 19 will drop 15 into this passage and flow therefrom into the passages 32 and thence to the crank case of the engine. To prevent the oil in the passage 36 from getting to the valve stems and working down thereon through their bearings into the inlet and exhaust passages and 20 past the valves into the combustion chamber, a boss 37 for each valve stem is formed integral with the bottom of the passage 36 and extends upwardly around the stem a short 25 distance into the lower end of the cap sleeve 19. As the valve stems and the walls of the passage 36 become heated during the running of the engine, an oil vapor will be formed in the passage and rise upwardly 30 in the several cap sleeves, thus effectually lubricating the valve springs and stems.

Between the neck portions which form the guides 21 for each pair of sleeves 19 for each cylinder, is an opening 38 and the 40 center opening 39 of these openings forms a transverse passage lying directly above the inlet 5 and the outlet ends of the outlet passages 7, 8 and 9. A cap or shield 40 is formed integral with the upper part of the 45 exhaust pipe or manifold 11 and side openings 41 in this cap adjacent to the pipe, permit the entrance of air into the cap and through the connecting passage 39 to a suitable pipe or passage 42 which is secured over 50 the end of the passage 39 at the opposite side of the engine and directly above the carbureter 12. This pipe 42 extends downwardly to a point opposite the air inlet end of the carbureter and is provided with a 55 suitable sleeve valve 43 having an upper open end and a closed lower end. The valve is also formed with side openings or slots 44 and 45, the slot 44 being adapted to register with an outlet opening 46 over which 60 the air inlet to the carbureter is secured; the pipe 42 also has an opening 47 in its outer side directly opposite the opening 46, and the openings in the sleeve valve are so arranged that they may be brought into 65 operative relation to the openings 46 and 47

to permit air to pass directly through the valve into the carbureter or the valve may be turned to close the opening 47 and permit air to be drawn through the open upper end of the valve, passage 39 and cap 40. As the 70 slots 41 in the cap 40 are located adjacent to the upper side of the exhaust pipe 11, the air passing therethrough into the cap will be rapidly heated and then pass directly across and into the carbureter at the opposite side of the engine. The valve 43 is operated by means of a stem 48 and any suitable connection (not shown) extending to a point where it may be conveniently manipulated by the operator of the engine. 75

By this arrangement a very compact overhead valve construction is secured and a thorough lubrication of the valve operating mechanism is provided without danger of the oil getting into the combustion chamber 80 of the cylinders, and by providing suitable means for supplying a continuous flow of oil to the crank shaft chamber, the parts are provided with a fresh supply of oil and the excess overflows and is conducted into 85 the crank case where it is used over again. The cap sleeves on the valve stems prevent the oil from getting onto the stems and being conducted thereby to the explosion chambers of the cylinders, and at the same 90 time form contact members for the several cams which are accurately guided in their movement and protect the valve stems against wear.

Rotary motion is imparted to the cam 100 shaft in timed relation to the movements of the several pistons in the cylinders, by means of a timing shaft 49 having a pinion 50 on its upper end engaging a bevel gear 51 on the end of the cam shaft, said gears 105 being inclosed within a suitable casing 52 formed integral with the end of the cam shaft chamber 22.

Obviously changes may be made in the construction and arrangement of parts without departing from the spirit of my invention and I do not limit myself to the construction and arrangement shown.

What I claim is:—

1. In an engine, the combination with a 115 cylinder having a port in its upper end, a guide bearing, and a valve to close said port having an upwardly extending stem guided in said bearing, of a sleeve having a closed upper end loosely engaging the upper end 120 of the stem, an oil chamber having a guide bearing in its bottom for the sleeve to guide the same independently of the stem, a cam in the oil chamber to engage the closed end of the sleeve, and a passage forming an oil 125 receiving chamber surrounding the stem at the lower end of the sleeve.

2. In an engine, the combination of a cylinder portion having a port and formed with a passage leading from the port, and a 130

guide for a valve stem, a valve to close the port having an upwardly extending stem engaging the guide, a member forming an oil chamber into which the upper end of the 5 stem projects and provided with a guide opening in its bottom, and an oil passage at the lower end of the guide bearing around the stem, a sleeve guided in the guide bearing having a closed upper end engaging the 10 upper end of the stem and guided independently of said stem, a spring within the sleeve to move the stem in one direction, and a cam in the oil chamber to engage the closed end of the sleeve and move the stem against the 15 action of the spring.

3. In an engine, the combination with a plurality of cylinders, of a cylinder portion formed with an inlet and an exhaust port for each cylinder, and passages leading to 20 and from said ports, valves to close said ports having upwardly extending stems, a member forming an oil chamber extending across the several cylinders and into which the upper ends of the stems project and a 25 cam shaft in the oil chamber having cams to operate the several stems, said cylinder portion being formed with a passage extending beneath the oil chamber and surrounding the several valve stems to receive oil 30 escaping from the chamber around the stems.

4. In an engine, the combination with a cylinder portion having ports and passages leading to said ports, of valves to close 35 the ports having upwardly extending stems, an oil chamber into which the upper ends of the stems extend, and a cam shaft in the oil chamber having cams to operate the stems, said cylinder portion being formed with a 40 continuous passage surrounding all of the stems, hollow bosses extending upwardly from the bottom of the passage and through which the valve stems extend to form guide bearings therefor, said passage serving to 45 drain away the excess of oil entering said passage from the oil chamber.

5. In an engine, the combination with a

plurality of cylinders, of a head formed with inlet and exhaust ports and passages leading to and from said ports, said head 50 being also formed with an oil chamber extending across the several cylinders with neck portions connecting the bottom of said chamber with the head, a transverse air passage being formed between two of the adjacent neck portions, valves to close the ports, upwardly extending valve stems on the valves having bearings in the cylinder portion below the neck portions, sleeves guided in the neck portions independently of the 55 valve stems and having closed upper ends projecting into the oil chamber, springs sleeved on the stems to hold the same in contact with the sleeves and move the valves in one direction, a cam shaft in the oil 60 chamber having cams to engage the upper closed ends of the sleeves and means for preventing the rotation of the sleeves in their bearings.

6. In an engine, the combination with a 70 plurality of cylinders, of a head formed with inlet and exhaust ports, and passages leading to and from said ports, an oil chamber extending across the head from end to end thereof with an oil passage extending 75 downward therefrom at each end of the head, a wall at each end of the chamber to maintain a level of oil in the chamber, valves to close the ports, valve stems on the valves extending upwardly into the bottom of the 80 oil chamber and cap sleeves for the valve stems slidable in bearing openings in the bottom of the oil chamber, said head being formed with a passage at the lower ends of said sleeves communicating at its ends with 85 the oil passages at the ends of the oil chamber.

In testimony whereof I affix my signature in presence of two witnesses.

EMIL A. NELSON.
